MANUALLY OPERABLE PUMP

Robert F. Rolsten, Dayton, Ohio (1436 Adirondack Trail, Kettering, Ohio 45409), and Harold H. Hunt, 5965 Manon St., La Mesa, Calif. 92041

Filed Dec. 18, 1969, Ser. No. 20,550

Term of patent 14 years

Int. Cl. D23—01

U.S. Cl. D23—14

FIG. 1 is a side elevational view of a manually operable pump embodying our new design, the opposite side being the same as the side shown;

FIG. 2 is a top plan view thereof;

FIG. 3 is a bottom plan view thereof;

FIG. 4 is an elevational view taken from one end thereof; and

FIG. 5 is an elevational view taken from the end opposite that shown in FIG. 4.

We claim:

The ornamental design for a manually operable pump, substantially as shown and described.
